(57) CLAIM

The ornamental design for a shirt for sports, as shown and described.

DESCRIPTION

FIG. 1 is a rear perspective view of a shirt for sports showing our new design;

FIG. 2 is a front view thereof;

FIG. 3 is a rear view thereof;

FIG. 4 is a right side view showing the shirt being worn with the head bent forward, and of which the left side view is a mirror image; and,

FIG. 5 is a rear perspective view showing the shirt for sports being worn.

The broken line in all figures is for illustrative purposes only and forms no part of the claimed design.
